[57] CLAIM

The ornamental design for a portable engine generator, as shown and described.

DESCRIPTION

FIG. 1 is a front elevational view of a portable engine generator showing my new design;

FIG. 2 is a rear elevational view thereof;

FIG. 3 is a top view thereof;

FIG. 4 is a bottom view thereof;

FIG. 5 is a right side view thereof; and

FIG. 6 is a left side view thereof.

FIG. 7 is a perspective view thereof;

FIG. 8 is a perspective view thereof with the handle in the raised position.

FIG. 1

FIG. 2

FIG. 3

FIG. 4

FIG. 5

FIG. 6

FIG. 7

FIG. 8
